UNITED STATES PATENT OFFICE.

GEORGE TEASDALE, OF KANSAS CITY, MISSOURI, ASSIGNOR TO LOUIS LACHS, OF KANSAS CITY, MISSOURI.

DESIGN FOR A HUMIDOR FOR CIGARS.

58,955.

Specification for Design.

Patented Sept. 6, 1921.

Application filed January 2, 1920. Serial No. 349,068. Term of patent 3½ years.

To all whom it may concern:

Be it known that I, GEORGE TEASDALE, a citizen of the United States, residing at Kansas City, in the county of Jackson and State of Missouri, have invented a new, original, and ornamental Design for Humidors for Cigars, of which the following is a specification, reference being had to the accompanying drawing, in which—

Figure 1 is a plan view of my new design.

Fig. 2 is a longitudinal section of the design.

I claim:

The ornamental design for a humidor for cigars, as shown.

GEORGE TEASDALE.
